(54) **LOOM SHUTTLES, MODE OF THROWING**

(76) Inventor: **John Goulding**

John Gantling
Letters Patent, Dated August 24, 1837.

The Laboratory referred to in these Letters Patent and
containing part of the same, containing a description in
the words of the said John Gantling himself of his
improvement in the mode of throwing the shuttle or shuttle-
throwing.

To all Persons to whom these Presents shall come, from
Hartford, in the County of Hartford
and Commonwealth of Connecticut aforesaid
Gentlemen Greeting.

Be it known that I, the said John Gantling
have invented, constructed and applied to me a new
and useful improvement in the mode of throwing the shuttle
or shuttle in weaving, and the nature of the said inven-
tion and the manner in which the same is to be per-
formed, are particularly described and recited in and
by the drawings hereto annexed and the following
description thereof - that is to say, the representation
of Fig. 1, letters A. are the tops or heads having so as
to turn freely on their centers of B.B. from the top
of those heads are attached loops or picker strings
C.C. the other end of said loops or picker strings
is attached to blocks or pickers, which serve to drive
the shuttle. D. is a shaft that leads from a pulley
attached to the bottom end of these heads to the rear
of B.B. these blocks receive their motion from
a horizontal shaft by a lever as is customary those
blocks take their motion from a shaft that goes
around twice to the right or left going back and
forward, as the shuttle passes out of the left hand
it goes into the right it carries the right hand picker

into the box, and then into the right-hand shuttle, so that when the end of the right-hand wire is bent again, it disengages the shuttle end of the right-hand box into the right-hand box by two or more shuttles connected to the end and different colored wire, so as that two or more shuttles may pass each other from right to right, these two fly shuttles must be interwoven with each other by a cross bar; this cross bar must have a back-and-forth side motion, so that when the cross bar moves to the right the right-hand wire operates on the right-hand shuttle, it will throw the shuttle from the right to the left until it moves to the left, then the left-hand wire takes the shuttle again and throws it to the right; in this case there is but one beam that comes in contact with a shuttle at one time, and this gives an opportunity to throw as many shuttles from one side in succession as may be wanted.

The side motion to the connecting bar may be given by a cam or any other method the engineer may think proper; there being two fly wires, a chance to throw the shuttle by the same shaft that operates the fly or beater, provided the fly is operated by a weight or single eccentric frame. If more than one shuttle is used the picker on the shuttle rod, must be carried back after throwing the shuttle across by a cam, spring or weight, attached to it, to give a chance for the shuttle box to shift and bring another shuttle to throw across in succession.

What I claim as new and as my improvement and invention is the application of a cam to throw a second fly or lever to that end shuttle

be applied upon a pottery or glass vessel
and give a glaze to the same than are the in
a liquid state the glaze being colored by it is added
in succession.

I declare that the above is a true specification
of my said improvement as above described and for
which, before this Office, I have heretofore applied
for and on the sixteenth day of August in the year
of our Lord, one thousand eight hundred and twenty
four.
